THREE FACE FOUNTAIN

Gerald W. Frasier, Sherman Oaks, Calif., assignor to John Drew, Gerald W. Frasier, and John O. Hruby, Jr., copartners, and Messrs. Drew, Frasier, and Hruby, all individually, doing business as Irrigation Engineering & Manufacturing Co.

Filed Nov. 25, 1968, Ser. No. 14,653

Term of patent 14 years

Int. Cl. D23—01

U.S. Cl. D23—13

FIGURE 1 is a plan view of the three face fountain showing my new design.

FIGURE 2 is a front elevational view in the direction of arrow No. 2 of FIGURE 1.

FIGURE 3 is a right side elevational view in the direction of arrow No. 3 of FIGURE 1.

FIGURE 4 is a side elevational view in the direction of the arrow No. 4 of FIGURE 1.

The discharge jets shown in broken lines are included for illustrative purposes only.

I claim:

The ornamental design for a three face fountain, as shown and described.
